COLLAPSIBLE CRIB

Sidney E. Pearson, Kansas City, Kans.

Application January 9, 1939, Serial No. 249,934

5 Claims. (Cl. 5—99)

This invention relates to articles of furniture in the nature of collapsible cribs and the primary object is the provision of structure in a folding crib which will permit relatively moving the end members and side members thereof, so that when collapsed, the crib will occupy a minimum amount of space and will be condensed into a package that is convenient to handle in shipping.

10 A yet further aim in this invention is to provide a collapsible crib wherein is incorporated novel structure for holding the parts of the crib in assembled relation, which structure is adapted to maintain the side and end members of the crib in a rigid operative condition when the structure is in use, yet will permit quickly and easily folding the crib into a bundle of minimum size so that the same may be transported either for the convenience of the manufacturer in shipping, or for fulfilling the requirements of the ultimate user.

25 A further aim of this invention is to provide a folding crib with a specially created coupling that is formed to pivotally receive and interconnect parts of a crib so that such parts may be easily assembled, will be securely held in place when the crib is in the operative position, yet will permit quickly collapsing the crib to a folded condition without the removal of locking elements or the like.

30 Minor objects of the invention will appear during the course of the following specification, referring to the accompanying drawings wherein:

35 Figure 1 is a top plan view of a collapsible crib made to embody the present invention.

Fig. 2 is a side elevation of the crib with parts broken away.

40 Fig. 3 is an end view of the crib with parts broken away.

Fig. 4 is an edge elevation of the crib when in the collapsed condition.

45 Fig. 5 is an enlarged transverse sectional view through the folded crib, taken on line V—V of Fig. 4.

Fig. 6 is an enlarged fragmentary elevational view of a specially formed coupling.

50 Fig. 7 is a central sectional view through said coupling.

Fig. 8 is a partial sectional view of the coupling.

55 Fig. 9 is a fragmentary side elevation of the crib at the zone of juncture at the lower rail of the side members and one of the legs.

Fig. 10 is a sectional view through said structure taken on line X—X of Fig. 9; and,

Fig. 11 is an enlarged fragmentary sectional view taken on line XI—XI of Fig. 1.

In constructing a collapsible crib to embody this invention, the same should be made of metal or some material that is strong enough to withstand the stresses exerted thereon in the specially formed coupling which will be more fully herein-after set down.

10 It has been found desirable to use aluminum or steel tubing, and the crib comprises a pair of end members 12. These end members 12 are each provided with legs 14 on the upper ends of which are disposed hollow couplings 16, the lower 15 portion 18 of which is slotted and provided with a pivot pin 20 which passes through the upper ends respectively of legs 14. The slots of couplings 16 are along the inwardly directed faces thereof so that legs 14 of end members 12 may 20 be folded to a substantially horizontal position as shown in Figs. 4, 5 and 7. These end members 12 further comprise an upper rail 22 and a lower rail 24 joined by rods 26 in the nature of those shown in Fig. 3.

25 Couplings 16 of one end 12 are provided with inwardly directed socketed bosses 28 that receive the ends of upper rail 22, the axis of which is in alignment with pins 20. In assembling the structure, pin 20 should be positioned first so that one end thereof is covered by rail 22, as seen 30 in Fig. 8.

35 A tie-bar 30 forms a part of each end member 12 and rigidly interconnects couplings 16 thereof. Rivets 32 secure the ends of tie-bar 35 30 to couplings 16, and when the crib is made to embody the preferred form of the invention illustrated in the drawings, tie-bar 30 is spaced above upper rail 22 of each end 12 respectively.

40 A bracket 34 mounted upon each leg 14 of end member 12 receives the end of bottom rail 24, and a rivet 36 rigidly secures this rail 24 in position. A perforated ear 38 integral with bracket 34 has an offset flat surface 40 thereon to cooperate with cap 42 carried by the adjacent end of lower rail 45 44 forming a part of side member 46. Each side member is provided with an upper rail 48 and the aforementioned lower rail 44, the latter being removably secured to leg 14 by bracket 34.

45 A stud 50 enters perforation 52 of ear 38 when 50 the crib is assembled and the longitudinally extended portion of cap 42 lies in the offset part of bracket 34 and against face 40 so as to impart rigidity at this point.

55 The ends of upper rail 48 of each side member 55

46 project into couplings 16, as illustrated in Figs. 7 and 8. Laterally extending boss 54 has a bore therethrough which communicates with the cavity in hollow coupling 16, and when rail 48 is 5 in place the end thereof is adjacent to the inner face of the wall of coupling 16 to preclude longitudinal movement in one direction. Laterally extending lugs 56 formed by ends of cross pins 58 preclude longitudinal movement of rail 48 10 in the opposite direction. Manifestly, rail 48 is journalled in coupling 16 for pivotal movement about its axis.

A sheet of canvas 60 is supported between lower rails 44 and 24 of side and end members 15 46 and 12 respectively. This canvas 60 is drawn taut by a plurality of springs 62 which interconnect canvas 60 and side rails. It has been found desirable to form a tube along the marginal edges of canvas 60 by hemming the same, within 20 which tubes are positioned rods 64 about which one end of each spring 62 may be hooked. The other ends of springs 62 are secured to side rails 24 and 44 as the case may be, through the medium of screw-eyes 66. When the collapsible 25 crib is in the operative position, shown in Figs. 1 to 3 inclusive, coupling 16 and legs 14 are in engagement to prevent outward swinging of the end members. The positioning of stud 50 in perforation 52 also precludes outward movement of 30 end members 12 from the normal vertical position.

When the crib is to be collapsed to the position shown in Figs. 4 and 5, springs 62 interconnecting the ends of canvas 60 and rails 24 of 35 end members 12 are first unhooked from their normally associated screw-eyes 66, lower rails 44 of side members 46 are drawn apart by flexing springs 62 so that the stud 50 may be withdrawn from perforation 52. Side members 46 40 may then be swung inwardly to a substantially horizontal position about the axes of upper rails 48. This movement is immediately followed by swinging end members 12 inwardly toward each other to an overlapped, substantially horizontal 45 position about the axes of pivot pins 26. Upper rails 22 will pivot about their axes as the end members 12 are moved to the collapsed position.

From the foregoing, it will be clear to one skilled in the art that the employment of the 50 specially formed coupling 16 permits moving the parts of a collapsible crib to and from the operative position without the employment of separate elements, such as screws, bolts, clamps or other units likely to become lost. After the crib 55 is set up it will be rigid and self-sustaining, and the bundle formed when the crib is collapsed will be small and easily transportable.

Having thus described the invention, what is 60 claimed as new and desired to be secured by Letters Patent is:

1. In a collapsible crib having a pair of end members provided with legs, and a pair of side members each provided with upper and lower side rails, means interconnecting the side members 65 and said end members comprising hollow couplings on the upper ends of the legs provided with a slotted lower portion; pivot pins securing the upper ends of the legs in place within the couplings for inward swinging movement to horizontal 70 positions into the slots of the couplings; and laterally extending lugs on the upper rails of the side members within the couplings to prevent endwise movement thereof, said upper rails being rotatable on their axes to enable the side members, of which they are a rigid part, to swing 75

inwardly into horizontal folded positions, said couplings and the legs of said end members being in engagement to prevent outward swinging of the end members when the latter are in the vertical position. 5

2. In a collapsible crib having a pair of end members provided with legs, and a pair of side members each provided with upper and lower side rails, means interconnecting the side members and said end members comprising hollow couplings on the upper ends of the legs provided with a slotted lower portion; pivot pins securing the upper ends of the legs in place within the couplings for inward swinging movement to horizontal 10 positions into the slots of the couplings; and laterally extending lugs on the upper rails of the side members within the couplings to prevent endwise movement thereof, said upper rails being rotatable on their axes to enable the side members, of which they are a rigid part, to 15 swing inwardly into horizontal folded positions, said couplings and the legs of said end members being in engagement to prevent outward swinging of the end members when the latter are in the vertical position, said end members each 20 having an upper rail, the ends of which are pivotally journalled in the brackets for rotation about their axes, said upper rails of the end members and the said pivot pins for the upper 25 ends of the legs being in axial alignment. 30

3. In a collapsible crib having a pair of end members provided with legs, and a pair of side members each provided with upper and lower side rails, means interconnecting the side members and said end members comprising hollow couplings on the upper ends of the legs provided with a slotted lower portion; pivot pins securing the upper ends of the legs in place within the couplings for inward swinging movement to horizontal positions into the slots of the couplings; and laterally extending lugs on the upper rails of the side members within the couplings to prevent endwise movement thereof, said upper rails being rotatable on their axes to enable the side members, of which they are a rigid part, to 35 swing inwardly into horizontal folded positions, said couplings and the legs of said end members being in engagement to prevent outward swinging of the end members when the latter are in the vertical position, said couplings at the ends 40 of the crib being rigidly interconnected by tie-bars disposed to form parts of the end members respectively, when the latter are in the vertical 45 position. 50

4. In a collapsible crib having a pair of end members provided with legs, and a pair of side members each provided with upper and lower side rails, means interconnecting the side members and said end members comprising hollow couplings on the upper ends of the legs provided with a slotted lower portion; pivot pins securing the upper ends of the legs in place within the couplings for inward swinging movement to horizontal positions into the slots of the couplings; and laterally extending lugs on the upper rails of the side members within the couplings to prevent endwise movement thereof, said upper rails being rotatable on their axes to enable the side members, of which they are a rigid part, to swing 55 inwardly into horizontal folded positions, said couplings and the legs of said end members being in engagement to prevent outward swinging of the end members when the latter are in the vertical position, said couplings at the ends 60 of the crib being rigidly interconnected by disposed to form parts of the end members respectively, when the latter are in the vertical position, said end members each having a rail below its tie-bar, the ends of which are pivotally journalled in the brackets for rotation about their axes, said rails and said pivot pins for the upper ends of the legs being in axial alignment.

5. In a collapsible crib having a pair of end members provided with legs, and a pair of side members each provided with upper and lower side rails, means interconnecting the side members and said end members comprising hollow couplings on the upper ends of the legs provided with a slotted lower portion; pivot pins securing the upper ends of the legs in place within the couplings for inward swinging movement to horizontal positions into the slots of the couplings; and laterally extending lugs on the upper rails of the side members within the couplings to prevent endwise movement thereof, said upper rails being rotatable on their axes to enable the side

members, of which they are a rigid part, to swing inwardly into horizontal folded positions, said couplings and the legs of said end members being in engagement to prevent outward swinging of the end members when the latter are in the vertical position, said couplings at the ends of the crib being rigidly interconnected by tie-bars disposed to form parts of the end members respectively, when the latter are in the vertical position, said end members each having a rail below its tie-bar, the ends of which are pivotally journalled in the brackets for rotation about their axes, said rails and said pivot pins for the upper ends of the legs being in axial alignment, said rails of the end members each having the ends thereof in sockets formed in the brackets, said tie-bars serving to hold the brackets in spaced relation to preclude accidental removal of the rail ends from within said sockets.
